UNITED STATES PATENT OFFICE.

LINDELL T. BATES, OF NEW YORK, N. Y.

DEPTH-SHELL.

1,312,227.

Specification of Letters Patent. Patented Aug. 5, 1919.

Application filed January 23, 1918. Serial No. 213,325.

To all whom it may concern:

Be it known that I, LINDELL T. BATES, a citizen of the United States, residing at New York, in the county of New York and

5 State of New York, have invented a certain new and useful Improvement in Depth-Shells, of which the following is a specification.

10 My present invention pertains to an improved so-called depth shell; that is, one which, when it reaches a predetermined depth in the water, will automatically function.

15 The main object of the invention is to provide a shell which is absolutely safe for handling, and which may likewise be discharged from a gun with equal safety and which, nevertheless, will explode when it has passed into the water a given depth, 20 and only then.

A further object of the invention is to produce a mechanism which will meet all service specifications and requirements as laid down by the Army and Navy.

25 With these and other objects in view, as will hereinafter appear, reference will be had to the annexed drawings, wherein:

Figure 1 is a longitudinal sectional view showing the parts in their locked or safe position previous to firing the shell from 30 the gun;

Fig. 2 a like view showing the parts in the positions which they assume after firing and during flight;

35 Fig. 3 a similar view, illustrating the position assumed by the parts upon impact of the shell with the water;

Fig. 4 an enlarged sectional view with the parts shown in firing or detonating position;

40 Fig. 5 a cross sectional view, illustrating the hydrostatically-controlled barrier in the same position as shown in Fig. 4;

Fig. 6 a perspective view of such barrier and one of the actuating pistons or dia-

45 phragms;

Figs. 7 to 10 inclusive detail sectional views showing the centrifugal lock for the striker or hammer;

Fig. 11 a detail sectional view, showing 50 a modified form of the piston and barrier;

Fig. 12 a side elevation of such parts; and

Figs. 13 and 14 detail views of a modi-

fied form of centrifugal lock.

Broadly stated, the invention may be said

55 to comprise an explosive shell having

associated therewith a firing-pin for the detonating charge, a lock operated by centrifugal action to release and permit said pin or striker to move forwardly when the shell is in flight to arm the same, and a 60 hydrostatically-controlled barrier for arresting the movement of the hammer or pin, said barrier acting, when the shell reaches a given depth, to release the striker and to allow it to be thrown or forced into 65 contact with the primer through the action of a spring which, when the shell hits the water, is placed under compression.

In the drawings and having reference to Figs. 1 to 10 inclusive, 1 denotes the shell 70 body, the forward end being broken away in Figs. 1 to 3, and charged with any approved type of explosive, not shown. Extending transversely of the shell and projecting into oppositely-disposed openings 75 formed in the walls of the shell, is a cross-block or element 2, and overlying the ends of said element and screwed into the shell body are cap-pieces 3, each having a valve-seat 4 formed therein. In each of the outer 80 ends of the element 2 there is formed a cylindrical chamber 5, the chamber (see Fig. 5) alining with the wall 6 formed in the cap 3 immediately below the valve-seat 4. A piston valve 7 is mounted in each chamber 85 90 95 100 105 110 115 120 125 130 135 140 145 150 155 160 165 170 175 180 185 190 195 200 205 210 215 220 225 230 235 240 245 250 255 260 265 270 275 280 15, though if desired the forward section of the tube may take the form of a separate member. In the construction illustrated the rear portion of the tube is shown as extending from the rear wall of the shell, but this is not essential, as all of the parts may be sustained by the member 2 and located well forward in the shell. The forward or innermost end of the tube forms a chamber 16, for containing the detonating charge, and at the rear end of the chamber is located a partition 17, having a central opening from which extends rearwardly a collar 18. The bore of the tube is slightly reduced at this point, forming a shoulder 19, and in such reduced section is mounted a sliding fulminate or cap-carrier 20, said carrier being provided with spring-actuated detents 21 (Fig. 4) adapted, when the carrier is moved forward under the action of impact of the shell with the water, to interlock with the shoulder 19 and hold the carrier directly against the end of collar 18. A spring 22, normally holds the carrier in its rearmost position against a shoulder 23.

26 The striker, hammer, or firing-pin is denoted by 24 (Fig. 1), and under safe position of the parts has its rear end supported in the bore 25 of tube 15, with its forward portion in contact with a centrifugally-operated safety device, shown in detail in Figs. 7 to 10. It may be said to comprise two oppositely-disposed, arc-shaped elements 26, 27, normally held in edge contact by a surrounding spring 28, the opening between the parts when in this position being less than the diameter of the striker. The members 26 and 27, when the shell is in flight, tend, through centrifugal action, to separate or to move from the position shown in Figs. 7 and 8 to that disclosed in Figs. 9 and 10. To maintain them in such position I may employ any suitable locking mechanism, that illustrated comprising arms or fingers 29, 40 pivotally connected at one end to the element 26, while the other end of each carries a pin 30, which takes into a slot or groove 31, formed in member 27, said groove terminating in an outwardly-extending section 32. 45 When the elements 26, 27 are separated the fingers or links 29 assume the position shown in Figs. 9 and 10, and when the shell ceases rotating, as it does when it enters the water, the spring 28 is prevented from drawing the parts together, by reason of the fact that the pins 30 at such time stand in the outwardly-extending groove section 32, and the limbs are prevented from swinging back toward the horizontal. 50 55 60 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

of the shell with the water, engage a shoulder 36, as in Figs. 3 and 4, and lock the plunger in its forward position, the spring 34, during such forward movement being placed under compression, as in Fig. 3, at which time the striker is held against the barrier (plates 12 and 13) and prevented from moving forward. When, however, the shell reaches a predetermined depth in the water, the pressure thereof on the piston valves or plungers 7, 7 will move the latter inwardly so as to bring their openings into register and permit the spring 34 to shoot the striker forwardly therethrough and into contact with the primer, exploding the same, and thereby causing a firing of the detonating or booster charge in the chamber 16, with a resultant explosion of the shell.

The distance the shell will travel beneath the surface of the water may be regulated and determined by turning the plungers and shortening or lengthening the screw connection between them and the barrier plates 12 and 13. When the screw connection is shortened the shell will pass a greater distance than would be the case when the connection is lengthened, for the reason that the pistons will have to travel a greater distance to bring the openings 14 into register to permit the shooting forward of the striker 24. By employing threads of a given pitch, the adjustment may be readily effected, and the degree thereof determined by imparting half-turns to the pistons in one or the other direction. An index-mark 37, Fig. 6, formed on the shell and the outer face of the piston facilitates ready adjustment.

While the springs 8 serve to hold the pistons in their outermost position, until the shell enters the water, centrifugal action (due to rotation of the shell) also acts to hold them outwardly.

In Figs. 11 and 12 a modified arrangement of the piston operating the barrier is shown. Instead of having a threaded connection between the piston-stem and the barrier, I provide means whereby the tension of the spring may be varied and the spring placed under greater compression when it is desired that the piston 40 shall move inwardly only upon a greater degree of hydrostatic pressure than would be the case where the spring was under a light compression. To this end the piston is provided with an inwardly-projecting skirt 41, which is externally threaded, and upon which is mounted a nut 42. The nut is provided with a lug 43, which works in a groove 44 formed in a bushing 45 which is screwed into the shell body. Said bushing serves to hold the piston in place and forms the cylinder with which the piston coacts. As will be noted, a spring 46 bears at one end against the fixed wall of the member 2, while its upper end bears against the under face of the

nut 42. A swivel connection is formed between the inwardly-projecting stem 47 of the piston 40 and the stem 48 of the barrier plate 49. Said barrier plates overlap, as best shown in Fig. 11, and are held against rotation by contact with each other and the adjacent wall of the member 2. By turning the piston 40 in one or the other direction, the nut is raised or lowered, and the degree of compression of the spring 46 is consequently affected. The position of the barrier plates, however, remains the same; this by reason of the swivel connection between the parts 47 and 48.

In Figs. 13 and 14 a modified form of centrifugal lock is shown, wherein the two segmental members are indicated, respectively, by 50 and 51, one member (say, 51) having attached thereto leaf or plate springs 52, the free ends of which, when the parts are in their closed or collapsed position, extend into slots or openings 53 formed in the opposite element 50. Said openings are shouldered adjacent their inner ends, as at 54. When the parts are thrown apart through centrifugal action, the free ends of the springs are withdrawn from the slots 53 and pass over and come to rest upon the shouldered portions 54; this by reason of the spring action of the members 52, thereby securely holding the parts in their separated positions, as shown in Fig. 14. An encircling spring 55 may be employed, though this is not essential as the parts, by reason of the spring action of the members 52, will under normal conditions retain the positions shown in Fig. 13. In other words, the slots 53, being slightly divergent or at an angle to each other, cause the springs 52 to draw the members 50 and 51 toward each other. So, too, with the guard shown in Figs. 7 to 10 inclusive, the surrounding spring 28 might be omitted.

While in Figs. 13 and 14 both springs 52 are shown as attached to one member, it is obvious that one spring may be attached to one member and the other to the opposite member.

I am aware that heretofore hand-thrown bombs having a hydrostatically-controlled mechanism to allow them to explode when they have reached a given depth have been devised, but I am not aware that a shell or projectile adapted to be fired from a gun and which will only explode when it reaches a given depth in the water has been produced, and such an arrangement I desire to claim broadly. The term "shell" as employed in the application should be interpreted in the light of this statement.

It is, of course, to be understood that the particular hydrostatic mechanism might be employed with hand-thrown bombs, in which event the centrifugal lock and the spring 22 would be omitted, the cap placed

in close relation to the booster charge, and provision made for placing the spring 34 under initial compression.

While I have described the construction somewhat in detail, it is manifest that the same may be modified without departing from the generic invention. Thus, any of the well-known and commercial centrifugal locks may be employed for holding the striker in safe position, and the hydrostatically operated barrier may assume a form other than that disclosed.

Having thus described my invention, what I claim is:

1. In combination with a shell; a striker for detonating the same; a barrier obstructing the movement of the striker into active position; a piston connected with the barrier, said piston being exposed and being movable under hydrostatic pressure to remove the barrier out of the path of the striker; and a spring adjustable as to tension for holding the piston against hydrostatic pressure.

2. In combination with a shell; a striker for detonating the same; a pair of opposed pistons extending to the outer face of the shell; and overlapping perforate elements connected to said pistons, said elements normally obstructing the movement of the striker but permitting the same to pass therethrough when the pistons are moved inwardly under hydrostatic pressure and the perforations in the elements are brought into registry.

3. In combination with a shell; a striker; a centrifugal guard preventing initial forward movement of the striker; a plunger; a spring interposed between said striker and plunger; a lock for holding the plunger forward and the spring under compression after impact; a barrier for the striker; and means associated with the barrier and adapted, when the shell has moved a given distance into a body of water, to remove the barrier and to permit the striker to be forced forwardly.

4. In combination with a shell; a chamber adapted to contain a detonating charge; a movable cap-carrier; a spring holding said carrier away from the detonating chamber; locking means adapted to hold the carrier in active position with reference to the detonating chamber when said carrier is moved forward under impact; a striker; a centrifugal guard preventing initial forward movement of the striker; a plunger; a spring interposed between said striker and plunger; a lock for holding the plunger forward and the spring under compression after impact; a barrier for the striker; and means associated with the barrier and adapted, when the shell has moved a given depth into a body of water, to remove the barrier and permit the striker to be forced forwardly.

5. In combination with a shell; a striker; and a centrifugal guard therefor, said guard comprising two members and a pair of springs, each spring being rigidly secured at one end to one of the members and passing into a slot formed in the opposite member, the slots having a shouldered portion against which the end of the spring bears when the parts are separated through centrifugal action.

6. In combination with a shell; a striker; and a centrifugal guard therefor, said guard comprising two members, one member having a pair of diverging slots formed therein with a shoulder at the inner end of each slot, and a pair of spring arms secured to the opposite member, said arms normally

closing toward each other and adapted to enter the slots aforesaid.

7. In combination with a shell; a detonating mechanism; and a hydrostatically-operated barrier for holding said detonating mechanism out of operation until the shell has passed into the water a given depth, said barrier comprising a piston-like member, a spring serving to hold the same outwardly against the pressure of the water, a nut having a threaded connection with said piston, and an element carried by said piston and extending into the path of the detonating mechanism.

In testimony whereof I have signed my name to this specification.

LINDELL T. BATES.
